PACKING APPARATUS

Frederick P. Wood, Adrian, Mich., assignor to
Simplex Paper Corporation, Adrian, Mich., a
corporation of Michigan

Application December 4, 1931, Serial No. 578,875

6 Claims. (Cl. 226—17)

This invention which relates to a packing apparatus is concerned particularly with a facing plate upon which is arranged a liner adapted to support a column of fruit, vegetables, or the like, preliminary to the application of an upside down basket wherein the pack is to be made. Among its advantages, my present apparatus is inexpensive, easy and expeditious to operate, and assures a satisfactory and uniform pack of the handled articles. In addition, the present improvements permit of self-adjustment of the liner in accordance with irregularities and variations in the shape and size of the basket wherein the pack is made, permit the use of a liner having a row of scallops along one edge, and generally simplifies and facilitates the packing operation. These and other objects, some of which will hereinafter appear, are attained by my invention of which certain embodiments are suggested in the accompanying drawings in the manner following:

Figure 1 is a perspective view of the facing plate forming part of my apparatus;

Fig. 2 shows in perspective a liner applied operatively to the facing plate;

Fig. 3 is a view in vertical section through the facing plate, liner and surrounding form, a single layer of fruit, vegetables or the like being arranged upon the facing plate;

Fig. 4 which is a similar view shows the column of fruit, vegetables or the like, built up to the top of the liner, the form removed, and an inverted basket placed over the liner to receive the pack;

Fig. 5 shows in vertical section the righted basket containing the pack, the facing plate, indicated by dotted lines, having been removed therefrom;

Fig. 6 is a fragmentary detail in section showing one side of the facing plate and the base of the prong which is mounted thereon;

Fig. 7 is a view in plan of my improved liner having a scalloped edge;

Fig. 8 which is a view in section similar to Fig. 3 shows the scalloped edge liner of Fig. 7, and an associated form, applied to a facing plate of modified construction;

Fig. 9 is a similar view in perspective with the form removed;

Fig. 10 is a view in plan of another form of liner;

Fig. 11 is an enlarged detail in elevation showing the free ends of the liner overlapped and locked in place; and

Fig. 12 is a view in vertical section through the locking prong applicable to the liner of Fig. 10.

The main units of the present apparatus comprise a facing plate A upon which is arranged a liner B adapted to receive temporary external support from a form C preliminary to application of a basket D wherein the pack is completed. The facing plate which is circular in form may be slightly concave to produce a crowned pack as is common practice. Adjacent the plate periphery is a drop wall 15 forming an annular shoulder beyond which extends a flange 16. Depending from the facing plate in the region of the shoulder is an annular wall 17 forming a support for the plate when rested upon a table, bench or other plane surface.

Combined with a facing plate of this general kind is a prong 20 upstanding adjacent the shoulder 15. The height to which such prong extends need only be sufficient to interlock the free ends of a split liner along its lower edge. The prong at its base is extended outwardly and then upwardly to provide a lip 21 which is spaced slightly from the prong. A convenient way of securing the prong to the facing plate is by a rivet 22 extended through the prong base and facing plate flange, as indicated best in Fig. 6. It may be noted, in passing, that two such prongs, disposed on opposite sides of the facing plate, may optionally be used to advantage in the manner to be presently explained.

The liner B, of which one form is shown in Fig. 2, may be produced conveniently from paper stock. It is of arcuate elongated shape (see Fig. 7), so that, when arranged about the facing plate, it will incline inwardly in cone fashion. In the liner may be formed a number of holes 25 for ventilating purposes, and additionally I provide two slots 26, preferably elongated in the direction of the liner length. One of the slots 26 may be positioned close to the liner end x which is lapped outermost, whereas the other slot 26 is positioned remote from the opposite and inwardly disposed liner end y. The two slots when brought in register may receive the prong 20, as shown in Fig. 2, whereby the liner is held in place. No further securing of the liner is required in view of the simple and effective lock provided, and of the extension of the inner liner end for a substantial distance beyond this point of locking. If desired, the inner liner end may have its top corner cut off, as shown, to obviate inward bending of the paper sheet at this point.

The form C is desirably made of sheet metal 55

tapered in cone fashion. Its opposite ends are preferably rolled or beaded, as shown, and in particular the bead 30 at its smaller end is rolled inwardly to overlie the proximate end of the liner and thereby prevent climbing of the latter. This is a common difficulty encountered in packing, particularly when the whole pack is shaken or jolted to settle the articles firmly in place. The form may rest upon the flange surrounding the facing plate during the building of a column of articles interiorly of the liner, after which it is withdrawn and replaced by an upside down basket which is later righted. After this last step, the facing plate with its attached prong, is removed, as indicated by the dotted lines in Fig. 5.

In the construction of Figs. 7, 8 and 9 I have shown an exactly similar liner having near its ends elongated slots 26 at unequal distances therefrom adapted to register when the liner is placed upon the facing plate. In addition, the liner under description has a further elongated slot 35 substantially midway between the other two. Its longer edge, i. e., the edge which lies proximate to the facing plate, is formed with scallops 36, the tabs thus produced being bendable along a common base line 37 which is desirably produced by scoring of the material. The facing plate A with which such a scalloped liner is used differs slightly from the construction shown in Figs. 1 to 5 inclusive, in that it lacks an annular shoulder and peripheral flange, and also the depending wall support, and instead utilizes a plurality of legs 38 that are placed inwardly an appreciable distance from the periphery of the plate. A prong 39 upstands from one side of the plate as does a second prong 40, preferably at the opposite side of the plate. This latter prong may be relatively short and if desired may terminate in a head 41, as shown best in Fig. 9. In all other respects the construction of the liner and facing plate is the same as that previously described.

In practice, the liner is applied around the facing plate with its scallops depending below the edges thereof. The support afforded by the legs 38 permits the scallops to lie below the plate and incline inwardly, if desired, as indicated in Fig. 8. In applying the liner to the plate, it will be found convenient to first position the slot 35 over the short prong 40 whose head 41 resists removal therefrom; the liner is thereafter wrapped around so that the slots 26 near its free ends may be brought into register to lock over the prong 39 in the manner already described. With the liner so positioned, and the scallops depending below the edge of the plate, the form is next applied following which a column of fruit, vegetables, or the like, is built up interiorly of the liner. After removal of the form, and substitution of the basket and inversion thereof, the facing plate is withdrawn permitting the scallops to be turned in for an attractive dress around the edge of the pack. By combining such a scalloped liner with a plate of the character noted, the scallops are positioned to lie above the completed pack exactly the proper distance for in-turning along the intended line of bend.

A further exemplification of my invention is shown in Figs. 10, 11 and 12 wherein the liner B is of somewhat different construction. Here I have shown a slot 45 substantially midway of the liner ends adjacent the longer edge thereof adapted to fit over a positioning prong, the same

as does the liner last described. Instead of openings near the liner ends adapted to register, as in the case of the liners already described, I provide notches 46 extending transversely into the liner from the longer edge thereof, these notches, by preference, being tapered somewhat. Such a liner is adapted for use with a facing plate A having a prong 47, as indicated in Figs. 11 and 12. Combined with this prong is a button 48 including a tongue 49 having a widened base, the tongue being positioned to the outside of the prong, spaced therefrom, and connected thereto by a rivet 50. The lower ends 51 and 52 respectively, of the prong and tongue may be out-turned to lie upon each other and upon the flange 53 of the facing plate to which they may be secured as by a bolt 54.

In locking the liner ends together, it is necessary merely that they be overlapped sufficiently for registration of the notches 46 whereupon they are ready for fastening to the button. This can be accomplished expeditiously by insertion of the fingers into adjacent centering holes 55 on opposite sides of the notches. The notches so being registered, the liner ends are receivable behind the widened tongue 49 and against the prong 47 with the button entering into the notches to secure the liner ends to the facing plate.

In each of the constructions described, the liner may be fitted expeditiously to the facing plate 30 whereon it is held with sufficient security to sustain a column of fruit, vegetables, or the like, during the interval between removal of the form and application of the inverted basket. In settling of the pack, the liner ends are free to slide within the basket to adjust for irregularities or variations in the size or form thereof, irrespective as to whether or not the facing plate be removed. This is due in part to the elongated or tapered character of the slots or notches wherein the prongs engage, and more particularly to the freedom of movement always preserved to the liner ends along its longer edge where the maximum of movement, incidental to settling of the pack, may occur. Not only is the present liner 45 self-adjusting in the manner explained, but no bending or assembling of parts either in the stage of manufacture or subsequently, is required.

I claim:

1. In a packing apparatus, the combination of 50 a facing plate about which may be fitted a split liner having overlapping ends and having registering slots in the lower portion of the liner adjacent its two ends, and an upstanding prong having its base affixed to the facing plate adjacent 55 its edge adapted to traverse the registering slots to connect the liner ends together, the prong being extended upwardly to a point substantially beyond the registering slots whereby to connect the liner ends when the liner is removed from 60 contact with the facing plate.

2. In a packing apparatus, the combination of a facing plate about which may be fitted a split liner having overlapping ends and having registering slots in the lower portion of the liner near 65 its opposite ends and a further slot intermediate of the liner ends, and upstanding prongs having their bases affixed to the facing plate adjacent its edge, one adapted to traverse the intermediate slot and the other to traverse the registering 70 slots to connect the liner ends together.

3. In a packing apparatus, the combination of a facing plate having a bottom support adapted to maintain the periphery of the plate at an elevation, the plate being adapted to receive there- 75

around a split liner having overlapped ends and bendable scallops formed along the bottom edge of the liner extending below the edge of the plate, there being registering closed slots near the liner ends, and an upstanding prong having its base affixed to the facing plate adapted to traverse the registering slots to connect the liner ends together, the prong being extended upwardly to a point substantially beyond the registering slots whereby to connect the liner ends when the liner is removed from contact with the facing plate.

4. In a packing apparatus, the combination of a facing plate around which may be fitted a split liner having overlapped ends and having registering slots near the liner ends and another slot intermediately of the liner ends, a prong upstanding from the facing plate adapted to traverse the registered slots to connect the liner ends together, and a second prong terminating in a head upstanding from an opposite side of the facing plate adapted to traverse the intermediate slot in the liner.

5. In a packing apparatus, a circular facing plate, two pointed prongs upstanding from the plate at spaced marginal points thereon, one prong being adapted for insertion through a positioning slot formed in a liner fitted around the facing plate and the other prong being adapted for insertion through registering slots in the overlapped end portions of the liner, the two prongs together acting to secure the liner accurately in place upon the facing plate.

6. In a packing apparatus, the combination of a facing plate and an associated open ended form having its walls inclined in cone fashion adapted to furnish external support to a liner which is rested on the plate and against the inner side of the form, there being means extending inwardly from the upper smaller end of the form adapted to overlie the proximate edge of an enclosed liner for preventing upward movement of the liner beyond the end of the form.

FREDERICK P. WOOD.
